US00D923159S

(12) **United States Design Patent** (10) Patent No.: **US D923,159 S**
(45) Date of Patent: **** Jun. 22, 2021**

(54) **SEAL MEMBER FOR USE IN SEMICONDUCTOR PRODUCTION APPARATUS**

(71) Applicant: **Valqua, Ltd.**, Tokyo (JP)

(72) Inventors: **Yong-Gu Kang**, Nara (JP); **Nobuhiro Yoshida**, Nara (JP)

(73) Assignee: **Valqua, Ltd.**, Tokyo (JP)

(**) Term: **15 Years**

(21) Appl. No.: **29/714,192**

(22) Filed: **Nov. 21, 2019**

Related U.S. Application Data

(62) Division of application No. 35/506,053, filed on May 14, 2018 (U.S. filing date under 35 U.S.C. 384), and having an international filing date of May 14, 2018, now Pat. No. Des. 897,504.

(57) **CLAIM**

The ornamental design for a seal member for use in semiconductor production apparatus, as shown and described.

DESCRIPTION

FIG. 1 is a perspective view of a seal member for use in semiconductor production apparatus, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a cross-sectional view thereof; and,

FIG. 9 is an enlarged cross-sectional view of a portion thereof.

1 Claim, 9 Drawing Sheets
